AUTOMOBILE DOOR HANDLE AND LOCK
MECHANISM

James Summers, Atlanta, Ga.

Application December 17, 1936, Serial No. 116,432

3 Claims. (Cl. 70—208)

This invention relates to certain new and useful improvements in automobile door handle and lock mechanism.

The primary object of the invention is to provide a handle and lock mechanism for the door of an automobile of the type wherein the latch bolt for holding the door in closed position is manually operable by handles respectively arranged at the inner and outer sides of the door, the outer handle being retractable into a recess at the outer side of the door to prevent access thereto for operation of the latch bolt, the outer handle being movable into its recess by direct pressure exerted thereon and also by the operation of devices carried by the handle at the inner side of the door and operatively engaged therewith.

Another object of the invention is to provide a handle and lock mechanism of the foregoing character for automobile doors having manually operable means associated with the handle at the inner side of the door for moving the handle at the outer side of the door into a retracted position within its recess and further to equip the inner handle with manually controlled latch devices permitting the automatic projection of the handle at the outer side of the door into operative or gripping position in spaced relation to the outer side of the door.

With the above and other objects in view that will become apparent as the nature of the invention is better understood the same consists in the novel form, combination and arrangement of parts hereinafter more fully described, shown in the accompanying drawings and claimed.

In the drawings:—

Figure 1 is a fragmentary elevational view of the inner side of an automobile door equipped with the improved handle and lock device;

Figure 2 is a fragmentary elevational view of the outer side of the door, showing the outer handle and key operated lock therefor;

Figure 3 is a longitudinal sectional view taken on line 3—3 of Figure 1, with the handle at the outer side of the door illustrated by full lines in a retracted position and seated within a recess at the outer side of the door and projected to operative position as illustrated by dotted lines with the devices associated with the handle at the inner side of the door for controlling the position of the outer handle;

Figure 4 is a longitudinal sectional view, partly broken away and shown in section, and taken on line 4—4 of Figure 3;

Figure 5 is a cross-sectional view taken on line 5—5 of Figure 3;

Figure 6 is a cross-sectional view taken on line 6—6 of Figure 3;

Figure 7 is a cross-sectional view taken on line 7—7 of Figure 3, and illustrating the handle operated barrel or shank and its connection with the latch bolt for the door;

Figure 8 is a cross-sectional view taken on line 8—8 of Figure 3, showing the lug and abutment 10 connection between the handle at the inner side of the door and the shank or barrel that operates the latch bolt; and

Figure 9 is a cross-sectional view taken on line 9—9 of Figure 3.

Referring more in detail to the accompanying drawings, the reference character 10 designates the door of an automobile and as shown in Figure 1, the inner side of the door 10 carries a casing 11 for housing the usual tensioned latch bolt 12 for engagement with a keeper on the door frame to retain the door in closed position. The latch bolt 12 is controlled in its operation by handles 13 and 14 respectively located at the outer and inner sides of the door 10, the handle 13 being mounted for movement toward and away from the outer side of the door 10 as illustrated by full and dotted line positions in Figure 3 and when in position adjacent the outer side of the door, the same is received in a recess 15 to present the handle 13 flush with the outer face of the door and inaccessible for gripping operation.

As shown in Figure 3, the edge 16 of the door 10 has a cylindrical opening 17 therein to accommodate the mounting of the latch mechanism and operating handles therefor, the edge 16 of the door adjacent the opening 17 being cut-away to provide a pocket 18 while an angle plate comprising walls 19 and 20 is secured to the edge of the door with the wall 19 engaged in the inner side of the door while the wall 20 engages the edge of the door. A guide cylinder 21 is anchored in the opening 17 and the inner end thereof is engaged with a rotatable cylindrical block 22 within the pocket 18 that has, as shown in Figure 7, a laterally projecting finger 23 extending into a side notch 24 carried by the latch bolt 12. The cylindrical block 22 as shown in Figure 3 has an annular groove therein and is journaled in the walls of an opening in the inner wall 19 of the angle plate and that portion of the block 22 outwardly of and adjacent the wall 19 as shown in Figure 8 carries a cam abutment 25 for purposes presently to appear.

The handle 14 at the inner side of the door 55

10 is of tubular formation and has an angle end 26 with a bearing 27 at the end thereof with an opening therein that is journalled on an extension of the cylindrical block 22 and is retained on said extension by devices to be presently described. The handle 14 is spaced from and parallel with the inner side of the door 10 and is guided in its movements by the strap guide 28. A lug 29 projects from the bearing wall 27 of the angle end 10 of the handle and is engaged with the abutment lug 25 on the cylindrical block 22 to effect rotation of the block 22 when the handle 14 is depressed for the operation of the latch bolt 12.

As shown in Fig. 3, the end of the outer handle 13 adjacent the opening 17 in the door 10 carries a cylinder 30 that is slideable and rotatable in the guide cylinder 21, the inner end of the cylinder 30 having a bottom wall 31 that forms an abutment for one end of a coil spring 32 within the inner end of the guide cylinder 21, the other end of the spring 32 being engaged with the inner closed end 21a of the guide cylinder. A tubular shaft 32 extends through an opening in the bottom wall 31 of the cylinder 30 and has an annular flange 33 engaged with the bottom wall 21a of the guide cylinder 21, the tubular shaft 32 inwardly of the collar 33 being rectangular in cross-section as shown at 34 in Figure 7, and extending through a similarly formed opening in the cylindrical block 22, the inner terminal end of the tubular shaft 32 extending into the angle end 26 of the handle 14 and being externally threaded for the reception of a nut 35 for retaining the handle 14 on the cylindrical block 22 as will at once be understood from an inspection of Fig. 3 of the drawings. A cylinder 36 is slideably mounted within the cylinder 30 with the inner open end thereof engaged with the bottom wall 31 of the cylinder 30 while the outer end wall 37 of the cylinder 36 overlies the outer end of the tubular shaft 32. A key rib 38 extends longitudinally of the tubular shaft 32 and is engaged in a key slot 39 in the end wall 31 of the cylinder 30, the tubular shaft 32 being keyed to the cylindrical block 22 and also to the cylinder 30.

A rod 40 extends through the tubular shaft 32, the outer end 41 of the rod extending through the outer end wall 37 of the cylinder 36 and being headed as shown in Figure 3. A chain 42 has one end attached to the inner end of the rod 40 and is trained over a guide pulley 43 in the angle end 26 of the arm 14, the other end of the chain being connected to a latch and control device for the outer handle 13. As shown more clearly in Figs. 3 and 4, the tubular inner handle 14 is diametrically slotted as at 44 intermediate the ends thereof and through which slots a cross-pin 45 extends, the outer end of the cross-pin 45 being anchored to a collar 46 slidably mounted upon the tubular handle 14. A resilient catch comprising a pair of diverging legs 47 and 48 connected by a loop or barrel 49 has the barrel attached to the pin 45, the free end of the legs 47 being attached as at 49a to the adjacent end of the chain 42 while the free end 50 of the leg 48 constitutes a catch engaged by an adjustable stop 51 carried by the tubular handle 14. A coil spring 52 of less strength than the spring 32 in the guide cylinder 21 has one end attached as at 53 to the cross-pin 45 and the other end attached to the cap 54 at the free end of the handle 14, the spring 52 acting to maintain the chain 42 in an extended position during movements of the outer handle 13 toward and away 75 from the door 10. When the latch 50 is in the

position shown in Figure 3 and engaged with the stop 51, the cylinder 30 carrying the outer handle 13 is in its withdrawn or retracted position with the handle 13 seated in the recess 15 against the tension of the springs 32 and 52. A releasing device is provided for the latch 50 and comprises an elongated arm 55 slidably mounted within the tubular handle 14, one end of the arm 55 carrying a laterally projecting block 56 slideable in a slot 57 in the tubular arm as shown in Figure 4 and operated by a button 58 secured to the block 57 exteriorly of the handle 14. Enlarged recesses 59 and 60 are formed respectively at opposite ends of the slot 57 into which the block 56 is movable for holding the arm 55 in its adjusted position. The other end 61 of the arm 55 underlies the leg 48 of the catch 50 and when shifted to the dotted line position shown in Figure 3 is adapted to release the catch 50 from its stop 51 and permits automatic projection of the outer handle 13 to the dotted line position shown in Figure 3.

A key operated lock 62 is mounted in the outer end of the cylinder 30 and includes a latch bolt 63 adapted to be received in a keeper socket 64 formed in the guide cylinder 21 as shown in Figure 3, for locking the handle 13 in its retracted position within the recess 15.

With the parts in the full line position shown in Figure 3, with the exception of the lock bolt 63 that is normally retracted into the lock casing 62, and it being desired to project the outer handle 13 from the interior of the automobile, the operator by means of the button 58 moves the block 56 out of the recess 59 and through the slot 57 in the handle 14 to position the block 56 in the forward recess 60, this movement causing the end 61 of the arm 55 to disengage the catch 50 from the stop 51 whereupon the spring 32 engaging the inner end 31 of the cylinder 30 automatically projects the cylinder 30 carrying the handle 13 to the dotted line position shown in Fig. 3. The main door latch bolt 12 may be operated by the inner handle 14 through the medium of the lug 29 carried thereby engaged with the cam abutment 25 on the rotatable or cylindrical block 22, and said latch bolt 12 may be also operated by the outer handle 13 through its cylinder connection 30 with the key rib 38 on the tubular shaft 32 and the keyed connection 34 of the tubular shaft with the rotatable cylindrical block 32. The outer handle 13 may be retracted into its recess 15 by first displacing the end 61 of the arm 55 relative to the catch 50 by positioning the block 56 at one end of the arm 55 in the recess 59 and thereafter moving the sleeve 46 over the inner tubular handle 14 to cause the headed end 41 of the rod 40 to move the cylinders 36 and 30 into the guide cylinder 21 and against the tension of the spring 32 until the catch 50 engages the stop 51. The outer handle 13 may be locked in its recess 15 by projecting the latch bolt 53 of the lock casing 62 into the keeper socket 64 in the guide cylinder 21.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope of the invention as claimed.

I claim:—

1. Latch mechanism for doors, including a latch bolt carried by a door, a handle at each side of the door for operating the latch bolt, the handle

- 5 at the outer side of the door being movable into a recess in the door to be rendered inaccessible, means carried by the handle at the inner side of the door for controlling the position of the handle at the outer side and for retracting the handle at the outer side of the door into said recess, the inner handle being of tubular formation, the outer handle being normally spring pressed outwardly, a tensioned catch slidable in the tubular handle and operatively connected with the outer handle, a stop on the tubular handle for the catch and a manually operable slide in the tubular handle for releasing the catch for automatic projection of the outer handle.

10 2. Latch mechanism for doors, including a latch bolt carried by a door, a handle at each side of the door for operating the latch bolt, the handle at the outer side of the door being movable into a recess in the door to be rendered inaccessible, means carried by the handle at the inner side of the door for controlling the position of the handle at the outer side and for retracting the handle at the outer side of the door into said recess, the inner handle being of tubular formation, the outer handle being normally spring pressed outwardly, a tensioned catch slidable in the tubular handle and operatively connected with the outer handle, a stop on the tubular handle for the catch and a manually operable slide in the tubular handle for releasing the catch for automatic projection of the outer handle.

15 3. Latch mechanism for doors, including a latch bolt carried by a door, a handle at each side of the door for operating the latch bolt, the handle at the outer side of the door being movable into a recess in the door to be rendered inaccessible, means carried by the handle at the inner side of the door for controlling the position of the handle at the outer side and for retracting the handle at the outer side of the door into said recess, the inner handle being of tubular formation, the outer handle being normally spring pressed outwardly, a tensioned catch slidable in the tubular handle and operatively connected with the outer handle, a stop on the tubular handle for the catch and a manually operable slide in the tubular handle for releasing the catch for automatic projection of the outer handle, means for holding the slide at its limit of movements in opposite directions, the connection between the catch and outer handle including a flexible element and a spring associated with the catch for maintaining the flexible element in a taut condition.

20 4. Latch mechanism for doors, including a latch bolt carried by a door, a handle at each side of the door for operating the latch bolt, the handle at the outer side of the door being movable into a recess in the door to be rendered inaccessible, means carried by the handle at the inner side of the door for controlling the position of the handle at the outer side and for retracting the handle at the outer side of the door into said recess, the inner handle being of tubular formation, the outer handle being normally spring pressed outwardly, a tensioned catch slidable in the tubular handle and operatively connected with the outer handle, a stop on the tubular handle for the catch and a manually operable slide in the tubular handle for releasing the catch for automatic projection of the outer handle, means for holding the slide at its limit of movements in opposite directions, the connection between the catch and outer handle including a flexible element and a spring associated with the catch for maintaining the flexible element in a taut condition, a cylinder carrying the outer handle and a key operated lock carried by the cylinder and including a lock bolt and a keeper in the door for the lock bolt.

25 5. Latch mechanism for doors, including a latch bolt carried by a door, a handle at each side of the door for operating the latch bolt, the handle at the outer side of the door being movable into a recess in the door to be rendered inaccessible, means carried by the handle at the inner side of the door for controlling the position of the handle at the outer side and for retracting the handle at the outer side of the door into said recess, the inner handle being of tubular formation, the outer handle being normally spring pressed outwardly, a tensioned catch slidable in the tubular handle and operatively connected with the outer handle, a stop on the tubular handle for the catch and a manually operable slide in the tubular handle for releasing the catch for automatic projection of the outer handle, means for holding the slide at its limit of movements in opposite directions, the connection between the catch and outer handle including a flexible element and a spring associated with the catch for maintaining the flexible element in a taut condition, a cylinder carrying the outer handle and a key operated lock carried by the cylinder and including a lock bolt and a keeper in the door for the lock bolt.

30 6. Latch mechanism for doors, including a latch bolt carried by a door, a handle at each side of the door for operating the latch bolt, the handle at the outer side of the door being movable into a recess in the door to be rendered inaccessible, means carried by the handle at the inner side of the door for controlling the position of the handle at the outer side and for retracting the handle at the outer side of the door into said recess, the inner handle being of tubular formation, the outer handle being normally spring pressed outwardly, a tensioned catch slidable in the tubular handle and operatively connected with the outer handle, a stop on the tubular handle for the catch and a manually operable slide in the tubular handle for releasing the catch for automatic projection of the outer handle, means for holding the slide at its limit of movements in opposite directions, the connection between the catch and outer handle including a flexible element and a spring associated with the catch for maintaining the flexible element in a taut condition, a cylinder carrying the outer handle and a key operated lock carried by the cylinder and including a lock bolt and a keeper in the door for the lock bolt.

JAMES SUMMERS.
